UNITED STATES PATENT OFFICE.

WILLIAM STEEL PARSONS, OF LADYWELL, ENGLAND, ASSIGNOR TO J. STONE & COMPANY LIMITED, OF DEPTFORD, ENGLAND.

APPARATUS FOR DISCHARGING ASHES, CLINKERS, OR OTHER REFUSE.

1,102,351.

Specification of Letters Patent.

Patented July 7, 1914.

Application filed February 3, 1913. Serial No. 746,021.

To all whom it may concern:

Be it known that I, WILLIAM STEEL PARSONS, a subject of the King of Great Britain, and resident of No. 131 Embledon road, 5 Ladywell, in the county of Kent, England, have invented new and useful Improvements in Apparatus for Discharging Ashes, Clinkers, or other Refuse, of which the following is a specification.

10 This invention relates to improvements in apparatus for discharging or ejecting ashes, clinkers or other refuse.

According to a prior arrangement the apparatus for discharging or ejecting refuse

15 comprised a hopper and a nozzle combination, and the refuse material was delivered by the hopper to a stream of water passing through the nozzle combination and the latter not only discharged the ashes but also

20 acted as an exhauster in connection with a motor device for opening and closing the hopper valve, or for controlling the flushing of the hopper, or for both purposes. This motor device operated, whenever the suction

25 action due to the flow of liquid through the nozzle combination was sufficiently powerful, to open either the hopper valve, or the flushing valve, or both, these valves being kept closed, normally, by means of a con-

30 stant pressure. According to these improvements the motor device or engine, which automatically operates the hopper valve controlling communication between the hopper and the discharge pipe, is pro-

35 vided with a preferably hollow piston or ram which fits loosely, and so to say floats, in its cylinder, water from the sea or other source being admitted to the cylinder for the purpose of floating or washing the pis-

40 ton, whereby it is practically impossible for grit from the hopper to enter the cylinder and score the latter or the piston, or to cause the piston to jam. The lower portion of the hopper is moreover suitably made in the

45 form of a valve, the plug of which is adapted in one position to close the hopper and in the other position to open it. The plug and its casing may, if desired, be so constructed and connected to the supply of flushing

50 water as to cut off the latter when the plug is closed. Moreover the plug may be made an easy fit so that water escapes all around and at the ends if desired, and consequently the

55 danger of grit or ashes penetrating between the plug and the casing thereof is minimized

or entirely obviated. Furthermore, if desired, the water supply to the motor device or engine cylinder, or the water supply to the hopper flushing valve, or both of these water supplies, may be normally entirely cut off until such time as the sea water valve at the outlet of the discharge pipe is opened. This may be done by connecting the valve controlling this supply or these supplies with the gate or other valve at the outlet of the discharge pipe in such a manner that the valve for the said supply or supplies can only be opened when the gate is nearly or wholly open.

In order to enable this invention to be readily understood reference is made to the accompanying drawings in which:

Figure 1 is a central vertical longitudinal section of an apparatus embodying the present improvements showing the automatic controlling arrangement in its closed position, which it occupies when the apparatus is inoperative. Fig. 2 is a transverse section upon the line II-II of Fig. 1. Fig. 3 is a view similar to Fig. 1 showing the automatic controlling arrangement in the open position which it occupies when the apparatus is in full operation. Fig. 4 is a plan of Fig. 1. Fig. 5 is a diagrammatic representation of an installation comprising the improved device illustrated by the preceding figures and Fig. 6 is a central vertical section to a larger scale of valve controlling mechanism seen to the left hand side of Fig. 5.

In the construction illustrated by the accompanying drawings by way of example, *a* is the water supply pipe and *b* is the discharge pipe leading to the sea. The nozzle combination comprises a contracting cone or nozzle *c* on the supply pipe *a* and an expanding cone or nozzle *d* on the inner end of the discharge pipe *b*, the expanding nozzle *d* having a slightly flared or coned mouthpiece *e* arranged as and for the purpose hereinafter described. The expeller is 90 preferably arranged beneath the floor *f* of the stokehold, and a selective grating *g* is preferably arranged in the hopper *h* so that waste materials passing into the hopper and through the latter to the nozzle combination 105 cannot exceed a certain size in any one of three dimensions, as will be hereinafter explained.

The bars of the grid are so arranged that the openings *j* formed between them are 110

of such a size as to prevent pieces or objects of unsuitable dimensions in either of two directions from passing through, and, as shown in Figs. 1 and 3, the bars are of such depth that their lower edges are more or less parallel to the sloping bottom of the hopper *h*. As the bottom of the hopper slopes in one direction, it follows that the bars are of gradually increasing depth toward the delivery side of the hopper. According to this arrangement, therefore, if any object which has a cross sectional area suitable for allowing it to pass through the grid, has also a length or third dimension which renders it unsuitable for delivery to the nozzle combination, such piece or object will be arrested by the grid arrangement, because the lower end of the object will come against the bottom of the hopper *h* while the upper end thereof still remains in one of the spaces *j* of the grid, and it will thus be impossible for that object to pass through the hopper to the delivery tube *k* leading from the hopper. If, as sometimes happens, a bolt or piece of firebar, for example, passes through the openings *j* of the grid *g* and is of such length that it would be liable to choke the discharge jet, such bolt or the like is arrested as described and not permitted to slide down the bottom of the hopper with the ashes, cinders and so on. Any other suitable form of hopper or receiver may be employed. The hopper is conveniently provided with a flushing pipe, or with a number of jet nozzles or orifices *l*, through which water is discharged to wash the ashes or other refuse down the sloping bottom of the hopper *h* and through the tubular delivery key *k* to the discharging stream of water at the point where it passes from the contracting cone or nozzle *c* to the expanding or flared nozzles *e* and *d*. The floor or bottom of the hopper is preferably not inclined so steeply as to cause the ashes to slide down without the assistance of the flushing water delivered through the nozzles or orifices *l*. If desired the bottom of the hopper *h*, or the delivery duct thereof, is formed, as at *m*, as a casing for a loosely fitting hollow plug cock *n*. This plug has a port *o* in its conical wall for the admission of material from the hopper *h* and has its large end open to the delivery tube *k*. The cock is also constructed with a partition *p* so that a compartment *q* is formed in the small end of the plug. Ports *r* and *s* are formed in this compartment for opening and closing the supply of flushing water to the nozzles or orifices *l*. For example, the cock *n* in the position shown admits water from a side connection *t*, shown in dotted lines, to a hollow space *u* beneath the hopper, which space *u* is in communication with the hollow space *v* at the back of the hopper, which space *v* supplies the nozzles

or orifices *l*. The casing *m*, or the liner *w* within the same, instead of being fitted loosely by the plug *n* may be large only in places so as to allow of leakage locally to wash away grit from between the plug *n* and the interior of the casing *m* or liner *w*. One end of this plug extends beyond the cock casing *m* and is provided with means such as a miter wheel *x* for turning it. The wheel *x* gears with another miter wheel *y* keyed to a vertical shaft *z* which passes through a tube or bearing fixed to the floor *f* and the upper end of said shaft is furnished with a hand wheel 2, Fig. 5, or the like. The valve plug *n*, as well as being an additional safeguard to the automatically operated hopper valve hereinafter described, may also be adapted for use when bilge water is being expelled, as will be described hereafter. In some cases the valve *n* may be dispensed with and the top of the hopper may be provided with a cover which may be bolted down, or held down by fastenings or which may be otherwise secured. The orifice of the discharge tube *k* of the hopper *h* is, as aforesaid, closed by an automatically operated valve 3 which is suitably flat and circular in form. This valve 3 may be provided with a scraper, or with several scrapers 4 to push away the ashes or materials which may be present in the orifice of the discharge tube *k* and with a circular squeegee 5, there being preferably two dished scrapers 4 with the squeegee 5 between them. The valve may have an india rubber packing or ring 6 or the like, or the seating of the valve may consist of a ring of packing material. There is also preferably a sparge pipe 7 with a jet or jets 8 serving the double purpose of washing the hopper valve 3 and its seating on the extremity of the delivery tube *k*. The hopper valve 3 is mounted on the end of a hollow differential piston 9 loosely fitting in a cylinder 10, the annular space 11 of which is in communication with the sea and is therefore subjected to the pressure due to the head of sea water corresponding with the depth at which the expeller is situated beneath the surface of the water. The sea water is admitted to the annular space 11 by way of a connection 12 shown in dotted lines in Fig. 1, but shown also in Fig. 5 in full lines, the connection 12 being supplied by a pipe 13 which can be put in communication with the sea suction pipe 14 of the expeller. That end of the cylinder 10 in which the large area of the piston 9 moves, is connected by a duct 15 to an exhausting nozzle or element. For example, the duct 15 leads into a casing 16 surrounding the nozzle pieces or cones *d* and *e* and the gap 17 between the two nozzle pieces or cones *d* *e* enables the nozzle combination to exhaust the interior of the casing 16 and 130

therefore the cylinder 10 by way of the duct 15. At the back of the hopper valve 3, another valve 18 may be formed and adapted to seat against and make joint with the 5 end of the cylinder 10 when the piston 9 is in its retracted position, as seen in Fig. 3, so that the end of the cylinder 10 is then closed by the valve 18 and leakage of water from the connection 12 is thereby prevented 10 from taking place past the piston 9 and into the space or gap between the oppositely tapering nozzles or cones *c* and *e* of the induced current apparatus, this gap 19 being in the space to which the ashes and waste 15 materials are delivered by the tube part *k*. The valve 18, moreover, serves to keep grit from entering between the cylinder 10 and the differential area piston 9. The valve 21 seen best in Fig. 2 for opening and closing 20 the supply of flushing water for the hopper *h*, is connected to the piston 20 movable in a cylinder 22 mounted on the cylinder 10. In the closed condition of the valve 3, the sea water which leaks past the large 25 end of the piston 9 passes through ports 23 in the cylinder 10 and is admitted by the port 24, Fig. 2, to the cylinder 22 so as to operate on the underside of the piston 20 therein. The upper end of the cylinder 22, 30 on the other side of the piston 20, is in communication by a duct 25 with the end of the cylinder 10. The cylinder 22 need not be mounted directly on the cylinder 10 but may be mounted upon any convenient support 35 and connected with the cylinder 10 by suitable connections.

When no stream passes through the nozzle combination *c d e*, if sea water be admitted 40 at the connection 12 it leaks past the piston 9 and acts upon the big area of the piston, thereby maintaining the latter in the position seen in Fig. 1 and keeping the hopper valve 3 closed. The water is also admitted to respective sides of the piston 20 by the 45 ports 23 and duct 25, and the effective pressure holds the valve 21 down upon its seat. If there be back flow of sea water through the pipe *b* and nozzle *d* the same will pass through the gap 17 between the nozzles *d* 50 and *e* into the casing 16, and through the duct 15 into the cylinder 10 and will have the same effect as water leaking past the piston 9 as just previously described. It will be noted that it is not possible for back 55 flow of sea water through the cone *e* and into space 19 to effect opening of the hopper valve 3, but on the contrary the tendency will be to keep the valve 3 closed. When a stream of water is forced through the pipe 60 *a* and nozzle combination *c e d*, the pressure upon the big area of the piston 9 is reduced because the water, having diminished pressure and high velocity in the cone *e*, sets up a suction through the aperture 17, casing 16 65 and duct 15, but the effective pressure con-

ditions upon the valve 21 and piston 20 remain the same as before. As the suction increases, however, the piston 9 is moved back, owing to the atmospheric pressure upon its small end, and to the effective pressure of 70 water entering at 12, upon the annular area of the piston. As soon as the enlarged end of the piston passes the ports 23, it will be noted that pressure water arriving by the connection 12 will enter through the ports 75 23 and act upon the underside of the piston 20, whereas the upper side of the piston 20 will be subjected to the suction effect of the stream passing through the nozzle combination, owing to the fact that the port of 80 the duct 25 is not covered by the piston 9 when the latter reaches the limit of its opening stroke. In this way the piston 20 is caused to rise and lift the valve 21, whereupon water passes through the chamber 26 85 and the pipe 26' to the flushing jet nozzles or orifices *l* by way of the side connection *t*. As long as the induced current apparatus 90 *c d e* is working properly, the suction is sufficient to maintain the piston 9 in the rearward position in which the hopper valve is fully opened and the piston 20 is in the raised position in which the flushing valve 21 is fully open, so that, during working, sea water entering the annular space 11 of 95 the cylinder 10, flows around and past the piston 9 and washes the same and also flows through the ports 23 connecting the two cylinders 10 and 22 past the flushing valve 21 and through the pipe 26' to the flushing 100 nozzles or jets *l* at the top of the hopper *h*. This annular space 11 is connected to the sparge pipe 7 by a pipe 27, so that during working a spray is maintained over the seat of the hopper valve 3. 105

The stream of water is suitably supplied to the pipe *a* by a rotary or centrifugal pump 28 driven by a steam turbine 29 or other motor, the suction pipe 30 of the pump 28 being connected to the sea by the pipe 14 open to the sea through a suitable connection 31, which latter may contain a strainer. The pipe to the sea has a valve 32 which controls the supply of water entering by the pipe 14, part of which water 110 passes into the pipe 13, and part into the pipe 30. The pipe 13 may be provided with a separate valve 33, and the pipe 30 with a valve 34, the last named being a valve which can be adjusted either to admit sea water 115 from the pipe 14 to the pump suction 30, or to place the last named in communication with the bilge pipe 35 so that, if the suction pipe 30 be cut off from the sea water pipe 14, the pump 28 may be used to 120 empty the bilge. 125

In order that the water supply to the connection 12, which supply is used for flushing the hopper and sparging the seat of the valve 3, may not be turned on until 130

the gate valve 36 in the discharge pipe *b* is opened, a valve 37 in the pipe 13 is operatively connected in the following manner as illustrated clearly in Fig. 6:—The gate 5 valve rod 38, which is adapted to turn or move the gate valve 36 in any suitable manner, is screw threaded at 38^a and is reciprocated by an internally screwthreaded miter wheel 39 mounted in a suitable bearing 39^a, 10 said miter wheel meshing with another miter wheel 40 keyed to a shaft 41 mounted in bearings and provided at its other end with a hand wheel 42 Fig. 5. The valve 37 for controlling the flushing water is suitably of 15 the lift or mushroom type and is normally closed by a spring 37^a surrounding its stem 37^b. The screw-threaded gate valve rod 38 is arranged in line with the stem 37^b of the valve 37 and is of such a length that 20 the gate valve must be fully opened or almost fully opened before the said rod 38 comes into contact with the stem 37^b of the valve 37 for the purpose of forcing the valve 37 from its seat. The rod 38 and miter 25 wheels 39, 40 are shown inclosed in a casing in Fig. 6 but the casing is omitted in Fig. 5 which is more or less of a diagrammatic nature. Thus the water is only admitted at the connection 12 after the gate valve 36 has 30 been opened, and is permitted to close before the gate valve 36 is closed. The flushing water can therefore only flow and wash the waste material down to the space 19 when the discharge valve 36 is fully opened to 35 permit of discharge of such material by the stream of water. Also the flushing water ceases and no more material is delivered to the discharging stream prior to the closing of the discharge or gate valve 36.

40 In operation and assuming the pump to be working, flow of water takes place through the primary or contacting cone *c* of the nozzle combination, across the gap or space 19, through the flaring cone *e*, 45 past the annular opening 17 and through the secondary cone *d*. The water in the pipe *a* has pressure which is transformed into velocity in the cone *c*, the water again acquiring pressure and losing velocity in the 50 cones *e* and *d*. Owing to the reduced pressure and velocity of the stream at the point 17 suction is applied to the chamber 16 and duct 15, so that water in the cylinder 10 of the piston 9 is withdrawn and carried 55 away by the stream of water, and the pressure on the large area of the piston 9 is diminished. The pressure of the sea water admitted at 12 and acting on the annular area of the piston or ram 9, causes the latter to move toward the left hand, Figs. 1 and 2, in the cylinder 10 and the hopper 60 valve 3 is slowly moved away from its seat. Although the hopper may be full of ashes and waste materials, however, none of these 65 are fed down into the space 19 until the

hopper valve 3 is drawn back, when the larger end of the ram 9 passes the ports 23 in the cylinder 10, whereupon sea water passes from the connection 12, by way of the annular space 11, to the space between the flushing valve 21 and piston 20. Meanwhile the stream of water having been exhausted the water from the cylinder 10 and therefore exhausting the space above the upper and larger area of the flushing 70 valve piston 20, the latter now rises and lifts the valve 21, and the sea water passes the valve 21 and is delivered, at a pressure corresponding with the head, to the flushing orifices or jets *l* at the upper end 75 of the hopper, thereby washing the ashes down the inclined bottom of the hopper *h*, through the tube *k*, and into the space 19 where they are taken up by the stream of water passing from the cone *c* to the cone *e* 80 and are discharged outboard through the pipe *b* and gate valve 36.

If at any time the pump 28 should break down or an obstruction should take place in any of the pipes or cones, the suction effect 90 aforesaid would cease, or be reduced, so that the pressure of the sea water admitted at the gap 17 would at once move the piston 9 forward whereupon the flushing valve 21 would at once close and immediately afterward the hopper valve 3 would be closed.

For discharging bilge water, a non-return valve is fitted in the pipe connection 43 which leads from the bilge into the side of the expeller casing at a point near the gap between the cones *c* and *e*. When the cock *n* is closed and air and material in the hopper are thereby prevented from passing through the delivery tube *k*, the suction created by the stream of water forced by the pump 28 through the nozzle combination *c*, *e*, *d*, causes the non-return valve to open and sucks in bilge water through the connection 43. As the valves 32 and 34 may be adjusted so that the pump 28 is delivering bilge water to the nozzle combination, it will be apparent that the bilge water drawn in at 43 will augment the quantity actually sucked up and delivered by the pump 28. In place of the valve *n* a cover may be provided for closing the grating *g* in an airtight manner, but as it is very convenient to have the grating *g* on a level with the floor, so that waste material can be swept or shoveled from the floor on to the grating it is 110 generally preferred to employ the valve *n* and to dispense with the cover which might offer an obstruction on the surface of the floor.

Access may be had to the jet chamber by 125 a hand hole which is normally closed by a cover 44 and the end cover 45 of the cylinder 10 may be removable in order to allow of the parts being readily inspected or repaired. Also the end cover 46 of the cyl- 130

inder 22 may be detachable to allow of ready access to the piston 20 and valve 21.

It is obvious that the apparatus can be varied considerably from the particular construction shown without departing from the essence and spirit of the present invention.

The details of the hydrostatic part of the apparatus, as well as of the mechanical part, are capable of being changed to suit particular circumstances and of being very greatly modified without departing from the invention.

I believe myself to be the first to employ in a hydraulic ejector a loose piston governing the ash valve, which latter is also a back-flow preventing valve, by means of a piston having a loose fit and constantly supplied with water which flows past the piston and maintains the same free from grit and obstruction and enables the piston to work smoothly and easily without interfering with the effective operation thereof. I believe myself also to be the first to employ a hollow floating piston for the purpose and also to employ a differential piston with water pressure always upon the small area and acting in the direction for opening the ash valve. I believe myself also to be the first to employ a flush controlling valve held to its seat by pressure and opened under the direct influence of the suction set up by the ejector. I also believe myself to be the first to control the operation of the flush-controlling valve by means of the piston aforesaid acting as a piston slide valve for distributing the pressure to a piston operatively connected with the flush-controlling valve.

I claim:—

1. Apparatus for discharging refuse into water comprising a hydraulic ejector combination, a cylinder having one end in communication with said ejector and its opposite end in communication with a water supply, a loosely fitting differential piston in said cylinder, and a valve operatively connected with said piston and controlling the admission to said ejector.

2. Apparatus for discharging refuse into water comprising a hopper, ejector nozzles in coöperative relation, a chamber inclosing a space between said nozzles and having communication with said hopper, a cylinder having one end in communication with one of said nozzles and its opposite end in communication with a water supply, a loosely fitting piston in said cylinder, and a valve operatively connected with said piston said valve being adapted to control the communication between said hopper and said chamber.

3. Apparatus for discharging refuse into water comprising a hydraulic ejector, a floating piston adapted to be moved in one direction by suction due to said ejector and

by pressure due to a head of water, and to be moved in the opposite direction by such head of water, and a valve operatively connected with said piston and adapted to control admission to said ejector.

4. Apparatus for discharging refuse into water comprising a hydraulic ejector, a cylinder, loosely fitting differential piston in said cylinder, a pressure connection for said cylinder on the side of the smaller area of said piston, a connection between said ejector and said cylinder on the side of the larger area of said piston, and a valve operatively connected with said piston and adapted to control admission to said ejector.

5. Apparatus for discharging refuse into water comprising hydraulic ejector nozzles in coöperative relation, a chamber inclosing a space between said nozzles, a cylinder, a loosely fitting hollow differential piston in said cylinder, an admission port at one end of said cylinder adapted to constantly admit pressure liquid to the small area of said piston a suction and back pressure port at the other end of said cylinder, a connection between the last named port and the hydraulic ejector and a valve in operative connection with said piston and adapted to control a refuse entry opening in said chamber.

6. Apparatus for discharging refuse into water comprising a hydraulic ejector nozzle combination, a chamber inclosing a space between nozzles of said combination, a cylinder, a loosely fitting differential piston in said cylinder, an admission port at one end of said cylinder adapted to constantly admit pressure liquid to the small area of said piston, a suction and back pressure port at the other end of said cylinder, a connection between the last-named port and one element of the hydraulic nozzle combination, and an annular valve mounted directly on the small end of said piston and adapted to control a refuse entry opening in said chamber.

7. Apparatus for discharging refuse into water comprising a hydraulic ejector nozzle combination, a chamber inclosing a space between nozzles of said combination, a cylinder, a loosely fitting piston in said cylinder, a trunk on said piston said trunk passing loosely through one end of said cylinder at which end is an admission port adapted to admit pressure liquid to the small area of said piston, a connection between the opposite end of said cylinder and one element of the hydraulic nozzle combination, and an annular valve mounted on the end of said trunk and adapted to control a refuse entry opening in said chamber.

8. Apparatus for discharging refuse into water comprising a hydraulic ejector nozzle combination, a chamber inclosing a space

between nozzles of said combination and having a refuse entry opening, a cylinder, a loosely fitting piston in said cylinder, a trunk on said piston said trunk passing 5 loosely through an opening in one end of said cylinder and entering said chamber, a valve seating around said refuse entry opening, a valve seating around the opening in the end of said cylinder, and reversely arranged valves on said piston adapted to close on to said seatings at respective ends of the stroke of said piston.

9. Apparatus for discharging refuse into water comprising a hydraulic ejector nozzle combination, a chamber inclosing a space 15 between nozzles of said combination, a hopper communicating with a refuse entry opening in said chamber, an automatically controlled valve operative to open and close 20 said refuse entry opening, and a selective grid arrangement in the mouth of said hopper, said grid arrangement having passages adapted to select objects according to three 25 different dimensions substantially as and for the purpose set forth.

10. Apparatus for discharging refuse into water comprising a hydraulic ejector, a chamber inclosing a refuse entry to said ejector, a hopper communicating at its bottom with a refuse entry opening in said chamber, water flushing means adapted to 30 wash refuse down said bottom to said entry openings, a valve adapted to normally close said opening but to be opened by suction set up by said ejector, a normally closed 35 valve controlling said water flush, and means connected with said flushing valve adapted to be directly influenced by the suction set up by the ejector for the purpose of opening said flush controlling valve.

11. Apparatus for discharging refuse into water comprising a hydraulic ejector, a chamber inclosing a refuse entry to said ejector, a hopper communicating at its bottom with a refuse entry opening in said chamber, water flushing means adapted to 45 wash refuse down the bottom of said hopper to said entry opening, a valve adapted to normally close said opening but to be opened by suction set up by said ejector, a flush controlling valve normally seated by 50 pressure applied thereto, and a piston connected with said valve and adapted to be influenced by the suction set up by said ejector for the purpose of opening said flush-controlling valve.

12. Apparatus for discharging refuse into water comprising a hydraulic ejector, a chamber inclosing a refuse entry to said 60 ejector, a hopper communicating at its bottom with a refuse entry opening in said chamber, water flushing means adapted to wash refuse down the bottom of said hopper to said entry opening, a valve, a differential piston connected with said valve and

adapted to normally close said valve over 65 said opening under pressure applied to the differential areas of said piston but to be opened by suction set up by said ejector, behind the larger of said differential areas, 70 a cylinder loosely inclosing said piston, a flush controlling valve normally seated by pressure applied thereto, and a piston connected with said valve and adapted to be placed under the suction influence of said 75 ejector by the movement of said differential piston in relation to ports in said cylinder under the action of the suction substantially as and for the purpose set forth.

13. Apparatus for discharging refuse into 80 water comprising a hydraulic ejector, a chamber inclosing a refuse entry to said ejector, a hopper communicating at its bottom with a refuse entry opening in said chamber, water flushing means adapted to 85 wash refuse down the bottom of said hopper to said entry opening, a valve, a differential piston connected with said valve and adapted to normally close said valve over 90 said opening under pressure applied to the differential areas of said piston but to be opened by suction set up by said ejector, behind the larger of said differential areas, 95 a cylinder loosely inclosing said piston and having in its walls a port arranged within the limit of the rearward stroke of said piston and a port arranged beyond the said limit, a connection between the rear end of said cylinder and said ejector, a casing on said cylinder, a piston in the upper part 100 of said casing, a flush controlling valve in the lower part of said casing, a connecting rod between said valve and the last named piston, a connection between the first named port and said cylinder at a point between 105 the connected valve and piston and a connection between the second named port and the top of said casing.

14. Apparatus for discharging refuse into water comprising a hydraulic ejector, a 110 chamber inclosing a refuse entry to said ejector, a hopper communicating at its bottom with a refuse entry opening in said chamber, a self-closing valve adapted to normally close said opening but to be 115 opened by suction set up by said ejector, and a revoluble plug valve arranged in the bottom of said hopper and adapted to control the communication between said hopper and said chamber independently of 120 the first named valve substantially as set forth.

15. Apparatus for discharging refuse into water comprising a hydraulic ejector, a chamber inclosing a refuse entry to said 125 ejector, a hopper communicating at its bottom with a refuse entry opening in said chamber, water flushing means adapted to wash refuse down said bottom to said entry opening, a valve adapted to normally close 130

said opening but to be opened by suction set up by said ejector, a normally closed valve controlling said water flush, valve operating means responsive to suction set up by said ejector and connected with said flushing valve, a hollow revoluble plug arranged in the bottom of said hopper and adapted to control the communication between said hopper and said chamber independently of the first named valve, said hollow plug having ports so disposed that when it opens communication between said hopper and said chamber it simultaneously opens a water supply to said flushing means.

16 16. Apparatus for discharging refuse into water comprising a hydraulic ejector, a chamber inclosing a refuse entry to said ejector, a hopper communicating at its bot-

tom with a refuse entry opening in said chamber, water flushing means adapted to 20 wash refuse down said bottom to said entry opening, a gate valve adapted to open and close the outlet from said ejector, operating mechanism for said gate valve, a flush control valve, and means in operative connection with said mechanism and adapted to open said flush control valve in arrear of the opening of said gate valve and to close said flush control valve in advance of the closing of said gate valve substantially as 30 set forth.

WILLIAM STEEL PARSONS.
